UNITED STATES PATENT OFFICE.

WILLIAM McMAHON, OF NORWICH, NEW YORK.

MILKING-STOOL.

1,122,143.

Specification of Letters Patent. Patented Dec. 22, 1914.

Application filed July 22, 1914. Serial No. 852,503.

To all whom it may concern:

Be it known that I, WILLIAM McMAHON, a citizen of the United States, residing at Norwich, in the county of Chenango and 5 State of New York, have invented new and useful Improvements in Milking-Stools, of which the following is a specification.

This invention relates to milking stools, and it has for its object to produce a device 10 of this class which will be simple in construction, clean and sanitary.

A further object of the invention is to produce a simple and efficient milking stool adapted to support the milk pail or receptacle adjustably with respect to the operator's seat.

With these and other ends in view which will readily appear as the nature of the invention is better understood, the same consists in the improved construction and novel arrangement and combination of parts which will be hereinafter fully described and particularly pointed out in the claims.

In the accompanying drawing has been 25 illustrated a simple and preferred form of the invention, it being, however, understood that no limitation is necessarily made to the precise structural details therein exhibited, but that changes, alterations and modifications 30 within the scope of the claims may be resorted to when desired.

In the drawing, Figure 1 is a perspective view of a milking stool constructed in accordance with the invention. Fig. 2 is a 35 bottom plan view of the same. Fig. 3 is a transverse sectional view taken on the line 3—3 in Fig. 2. Fig. 4 is a sectional detail view taken on the line 4—4 in Fig. 2.

Corresponding parts in the several figures 40 are denoted by like characters of reference.

The frame of the stool comprises two side members 15 having rearwardly diverging portions 16. The side members with their rearwardly divergent portions may be 45 formed of a single piece of wire, the same being bent to form at the forward end thereof of a U-shaped loop which is bent downwardly to form a leg or supporting member 17. At the rearward ends of the divergent 50 portions 16 are formed downturned loops constituting legs or supporting members 18, each of which, however, has a limb provided with an upward extension 19, said extension portions being securely connected at their 55 upper ends with the underside of the seat 20. 21 is a clamp block which is bored longitudi-

nally for the passage of the side members 15 upon which said clamp block is mounted adjacent to the divergent portions 16. Said clamp block is also bored vertically for the 60 passage of a supporting member 22, the upper extremity of which is secured to the underside of the seat 20, while the lower end of said supporting member is secured in the clamp block by fastening members, such as a 65 set screw 23. The side members 15, which are disposed in substantially parallel relation to one another, support a slide 24 which is adapted to support a milk pail 25, said slide consisting of a ring having a pail supporting flange 26 and provided below said flange with notches 27 to engage the side members 15. Extending diametrically across the slide transversely of the side members 15 and below the latter is a resilient 70 assembling member which may consist of a wire 28 that serves to assemble the slide with the frame and to retain the slide frictionally at any desired point of adjustment. 75

It will be seen that a person occupying 80 the seat 20 may adjust the pail supporting slide to any position that will be found most convenient in use.

The improved milking stool is extremely simple in construction and of such a nature 85 that it may very easily be kept in a clean and sanitary condition.

Having thus described the invention, what is claimed as new, is:—

1. A milking stool comprising spaced side 90 members having rearwardly divergent extensions, downwardly extending ground engaging feet at the forward ends of the side members and at the rearward ends of the extensions, and upwardly extending supporting legs. 95

2. A milking stool comprising a frame formed of wire and including spaced side members having rearwardly divergent extensions, a downturned connecting loop at 100 the forward ends of the side members constituting a ground engaging foot, downturned loops at the rearward ends of the divergent extensions constituting ground engaging feet and having upwardly extending seat supporting limbs, a clamp block connecting the side members adjacent to their rearward extensions, said block having a vertical bore, and a seat supporting member secured in said bore. 105

3. A milking stool comprising spaced frame members, downwardly extending

ground engaging feet and upwardly extending seat supporting legs, in combination with a slide supported on the spaced frame members.

- 5 4. In a milking stool, a frame comprising spaced frame members having forward portions arranged in substantially parallel relation and rearward divergent portions, ground engaging supporting feet at the forward ends of the side members and at the rearward ends of their divergent extensions, and seat supporting legs extending upwardly with respect to the frame, in combi-

nation with a pail supporting slide consisting of a ring having an annular supporting flange, notches to engage the parallel side members of the frame, and a resilient assembling member extending diametrically across the slide and transversely beneath the side members of the frame. 15

In testimony whereof I affix my signature in presence of two witnesses.

WILLIAM McMAHON.
